UNITED STATES PATENT OFFICE

169,698

AUTOMOBILE DOOR HANDLE AND LOCK
PROTECTIVE GLOVE

James K. Rogers, Chicago, Ill.

Application May 28, 1952, Serial No. 19,917

Term of patent 3½ years

(Cl. D10—8)

To all whom it may concern:

Be it known that I, James K. Rogers, a citizen of the United States, residing at Chicago, county of Cook, State of Illinois, have invented a new, original, and ornamental Design for an Automobile Door Handle and Lock Protective Glove, of which the following is a specification, reference being had to the accompanying drawing, forming a part thereof.

On the drawing:

Figure 1 is a view in side elevation of an automobile door handle and lock protective glove showing my new design;

Figure 2 is a top plan view of the device shown in Fig. 1;

Figure 3 is a bottom plan view of the device shown in Fig. 1; and

Figure 4 is an end view of the device shown in Fig. 1.

I claim:

The ornamental design for an automobile door handle and lock protective glove, as shown.

JAMES K. ROGERS.
